UNITED STATES PATENT OFFICE.

FRANKLIN H. ELWELL, OF CHICAGO, ILLINOIS.

SPARK PLUG.

Application filed March 29, 1920. Serial No. 369,828.

To all whom it may concern:

Be it known that I, FRANKLIN H. ELWELL, a citizen of the United States, residing at Chicago, in the county of Cook and State of Illinois, have invented certain new and useful Improvements in Spark Plugs, of which the following is a description.

My invention belongs to that general class of devices known as spark plugs. The invention has among its objects the production of a device of the kind described that is simple, convenient, durable, reliable, efficient and satisfactory for use wherever found applicable. It has particularly as an object 15 the production of a spark plug of the kind described which may be easily cleaned or the parts renewed without in any way disturbing the gastight joints which may be made permanent. The invention has among 20 its objects the production of a plug of a kind described that will not easily become fouled and short-circuited, and which will stand a great amount of heat without danger of breaking or becoming inoperative 25 or inefficient. Many other objects and advantages of the construction herein shown and described will be obvious to those skilled in the art from the disclosure herein given.

To this end my invention consists in the 30 novel construction, arrangement and combination of parts herein shown and described and more particularly pointed out in the claims.

In the drawings, wherein like reference 35 characters indicate like or corresponding parts,

Figure 1 is a sectional view through one form of my device;

Figure 2 is a similar view of a slightly 40 modified construction of the electrode sleeve;

Figure 3 is a sectional view illustrating another modified form of sleeve;

Figure 4 is a sectional view similar to 45 Figure 1 illustrating another construction similar to the preceding; and

Figure 5 is an end elevation of the plug shown in Figure 1.

Referring to the drawings, 1 represents a body part of suitable size, shape and material which is provided with an extending portion threaded as at 2 for insertion into and engagement at the spark plug opening on the engine, the same being preferably formed as at 3 so that it may be engaged 55 by a suitable wrench and turned down into place. The body part is preferably tubu-

lar, as shown, the same being formed with the opening enlarged at the outer end as indicated at 4 so as to provide a shoulder 5. Arranged in the recess at the outer end is a 60 core or part 6 of suitable material, preferably insulating material such as porcelain or the equivalent. An asbestos copper gasket 8, or the equivalent, is arranged at the inner end of the porcelain and a gasket or copper, or equivalent, ring 10 is arranged at the shoulder 7, the body end being turned over as indicated at 9 so that the porcelain or the like is securely and substantially permanently locked in place, and a gastight 70 joint secured between the porcelain and body. Arranged in the porcelain is an electrode, the inner portion 12 of which is preferably formed so as to be permanently retained in the porcelain, for example, cast 75 therein, while the outer end 11 constitutes a binding part. The inner end of portion 12 is recessed and internally threaded. Detachably carried by the electrode 12 is an electrode 15, the same extending from the 80 porcelain body to the inner end of the body 1. The inner end of the porcelain core 6 is preferably recessed, as shown, and in the preferred construction is shouldered as at 6'. As will be noted, the inner end of 85 the electrode 15 is threaded as at 16. The outer end is provided with a head 17 which is shown with an opening or hole 20 through the same. At the head end is provided a plate 18 or its equivalent arranged to cooperate with the electrode or contact members 19 carried by the body. The electrode 15 is shown provided with an insulating covering consisting of the sleeve parts 21, 22 being disks extending to adjacent the walls of the bore of the body. A disk 22 is also provided by the head and adjacent sleeve 21 at the open or inner end of the plug. The sleeve parts 21 may be made of mica, or the equivalent, the disks 22 95 being also preferably of mica of the desired thickness and size.

The construction shown in Figure 2 is similar, 25 representing the detachable electrode which is threaded as at 26 to engage 105 the cooperating electrode part in the porcelain core or body. The electrode is provided with the head 27 and plate 28 similar to that described. In this case, however, the sleeve 30, instead of being sectional, is in 110 one piece, only one disk 29 being employed. Another modified sleeve construction is

shown in Figure 3 in which 31 represents a sleeve, in this case preferably of porcelain or like material, provided, however, with ends 32 and 33 of mica or like material 5 which may be compressed or will yield upon expansion of the sleeve.

Referring to the construction illustrated in Figure 4, 36 represents the body of metal or the like having the projecting or inner 10 end threaded at 37 for engagement with the plug opening in the engine. The body 36 carries a core 38 of porcelain or the equivalent, 39 and 40 being rings of asbestos or copper for sealing and preventing leakage between the porcelain and the body. In 15 the core 38 is an electrode 41 provided with an enlarged end 42 internally threaded and with the exterior end 43 projecting to the exterior of the porcelain for a binding post. 20 Electrode 41 is preferably embedded in the porcelain body 38. A cooperating electrode member 44 is provided, the same being arranged to engage a threaded recess in the head 42 of the electrode 41. It will be 25 noted that the body of the porcelain 38 is recessed as at 46, the same extending, however, as at 45 so as to form a shoulder and a transversely extending portion between the recess and the end of the electrode head 30 42. Arranged on the electrode 44 is a sleeve 47 of porcelain or the like, 48 and 50 being bushings or packing members of mica or like material which may be arranged at the inner end of the sleeve and between the 35 sleeve and head 49 of the electrode. In this case the sleeve is shown with a projecting rim or flange 51. The head 49, as shown, carries a plate 52 and the body 36 carries one or more pins 53 at the inner end of the 40 body part.

With the construction shown in Figure 1, the device is applied to the engine, and electrically connected in the usual manner. The current passes through electrodes 12 and 15 45 and plate 18, and jumps across to the members 19 and flows into the body and thence to the ground. While the mica disks 22 may have a tendency to vibrate, thus preventing the accumulation of carbon, they 50 become incandescent and burn off the carbon preventing the accumulation thereof, and preventing the same from short-circuiting the plug and reducing its efficiency. To clean the plug it is only necessary to detach the electrode 15 and this may be done 55 by inserting a tool at the hole 20, turning the same, or by using pliers or a wrench or any equivalent for the purpose. The operation of the plug shown in Figure 2, 60 or the plug with a sleeve shown in Figure 3, is substantially similar. It will be noted that the core 6 is not removed in cleaning the plug and being permanently set or fixed in the body part, the same having been made 65 gastight remains gastight.

With the construction shown in Figure 4, in use the plug operates similar to the one previously described. The same may be easily cleaned by removing electrode 44. It will be noted that with the construction 70 shown in Figure 4, while a gastight and non-leaking joint is formed by the disk 48 and disk 50, that, should there not be a tight fit at the disks, gas would have to travel downwardly, and thence inwardly 75 toward the electrode 44, and thence downwardly, and thence outwardly and downwardly, and thence inwardly, and thence outwardly along electrode 41. The electrode 41 is, however, permanently formed 80 in the body 38, consequently there is small chance for leakage for the gas must travel the tortuous path described, and a portion would substantially always be tight. Owing to the yielding of the non-combustible 85 packing 48 and 50, expansion of the sleeve 47 is possible without fracturing the sleeve. With this construction the thin rim 51 becomes incandescent and tends to burn off any carbon and oil accumulating about the 90 open end of the plug. The same may be easily cleaned by removing the electrode and sleeve should the same be desired or found necessary at any time. The detachable 95 electrode and type of sleeves shown in Figures 1 to 3 may be substituted for that shown in Figure 4, if desired.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a spark plug of the kind described and in combination, a metallic body part having an opening therethrough, a core of insulating material arranged in said body part and projecting therefrom at the outer end thereof, gaskets arranged between the body and core, means for substantially permanently and inseparably securing said core in place, an electrode comprising two parts detachably connected together, one part permanently imbedded in said core between its ends so as to be integral therewith and projecting therefrom at the outer end thereof, the inner end of said electrode part enlarged and provided with a threaded recess, said core recessed at its inner end and having an opening connecting with said recess and with the recess in said electrode. The other electrode part being of a size to closely fit within said opening and threaded so as to engage with said recess of the first mentioned electrode part, said second elec- 105

- trode provided with a head at its opposite end and flanged about said head, a sleeve of insulating material arranged between the head of the second electrode and engaging 5 the bottom of the recess in said core, and provided with a very thin flange of insulating material extending outwardly to adjacent the inner wall of the opening in the body part.
- 10 2. In a spark plug of the kind described and in combination, a metallic body part having an opening therethrough, a core of insulating material arranged in said body part and projecting therefrom at the outer 15 end thereof, gaskets arranged between the core and body, an electrode carried by said core and projecting therefrom at the outer end thereof, the inner end of said electrode constructed to engage a cooperating part, 20 said core recessed at its inner end and hav-
- ing an opening therethrough registering with the recess in said electrode, a cooperating electrode part of a size to extend through said registering openings and constructed to engage with the first mentioned electrode, 25 said second electrode provided with a flanged head at its opposite end, a sleeve of insulating material in the bottom of the recess of said core and engaging the head of said second electrode, and yieldable gaskets 30 of flexible insulating material arranged at the end of said sleeve between the sleeve and core and the head of said second electrode.
- In testimony whereof, I have hereunto signed my name in the presence of two sub- 35 scribing witnesses.

FRANKLIN H. ELWELL.
